H. C. MILLER

LOOSE LEAF BINDER

Filed July 17, 1925

UNITED STATES PATENT OFFICE.

HENRY C. MILLER, OF MILWAUKEE, WISCONSIN.

LOOSE-LEAF BINDER.

Application filed July 17, 1925. Serial No. 44,273.

To all whom it may concern:

Be it known that I, HENRY C. MILLER, a citizen of the United States, and resident of Milwaukee, in the county of Milwaukee, and State of Wisconsin, have invented new and useful Improvements in Loose-Leaf Binders, of which the following is a description, reference being had to the accompanying drawings, which are a part of this specification.

This invention relates to certain new and useful improvements in loose-leaf binders and refers more particularly to the provision of improved means for readily releasably attaching the extension binder posts to the upper binder head.

In the loose-leaf binder art it is of importance that the construction be reduced to its simplest possible form to eliminate all unnecessary expense and, at the same time, convenient means must be provided for the ready adjustment of the binder capacity to accommodate any number of sheets. Having the above features that are desirable in a commercially successful loose-leaf binder in mind, this invention has as one of its objects the provision of an improved construction wherein a locking lug cooperates with a locking recess to connect each post with the upper binder head.

Another object of this invention resides in the provision of an improved loose-leaf binder post having means for maintaining a tension on its connection with the upper binder head to prevent the accidental releasing of the binder.

A further object of this invention resides in the provision of an improved binder construction of the character described in which each post is provided with a transverse recess or opening adapted to receive a pin or locking member carried by the upper binder head to readily releasably secure the post to the head.

With the above and other objects in view which will appear as the description proceeds, my invention resides in the novel construction, combination and arrangement of parts substantially as hereinafter described

and more particularly defined by the appended claims, it being understood that such changes in the precise embodiment of the herein disclosed invention may be made as come within the scope of the claims.

In the accompanying drawing, I have illustrated several complete examples of the physical embodiment of my invention constructed according to the best modes I have so far devised for the practical application of the principles thereof, and in which:

Figure 1 is a view looking at the rear end of a loose-leaf binder embodying my invention, portions thereof being broken away and in section to more clearly illustrate structural details;

Figure 2 is a fragmentary view of a portion of a loose-leaf binder looking thereat from the rear, said view being partly in section and partly in elevation;

Figure 3 is a fragmentary top plan view illustrating one end of the upper binder head of a loose-leaf binder equipped with a further modified form of my invention, a portion of the binder post being broken away and in section;

Figure 4 is a fragmentary view in elevation, partly in section, taken through Figure 3 on the plane of the line 4-4, and illustrating the construction of the attaching end portion of the post, the post being detached from the loose-leaf binder;

Figure 5 is a view similar to Figure 2 of a further modified form of my invention, and

Figure 6 is a view similar to Figure 5 of still another modified form of my invention.

Referring now more particularly to the accompanying drawing, in which like numerals designate like parts throughout the several views, the numerals 5 and 6 designate, respectively, upper and lower binder heads adapted to hingedly mount cover members 7, but one being shown, between which a body of leaves 8 is adapted to be confined by one or more binder posts 9 connecting the binder heads 5 and 6 in the manner to be described.

The binder heads are preferably formed

from sheet metal and their ends are closed by caps 10 from which project laterally lugs 11, see Figure 3, to receive the hinge rods or pintles 12 of the cover 7. The 5 lower head 6 is preferably closed on all sides and the lower ends of the posts 9 are threadedly connected therewith in a suitable manner, one form being by a screw 13, see Figure 5. The free end portions of the 10 posts pass upwardly through openings 14 in the upper binder head to extensively lie within the channel 15 of the head, the channel preferably being normally opened, although it may be provided with a suitable 15 cover, not shown.

The binder posts' free end portions are readily releasably connected with the upper head to lock the binder against extension by means of locking lugs or studs 16 adapted 20 to be engaged in receiving recesses 17, and in the forms of my invention illustrated in Figures 1 to 5, inclusive, the studs 16 are fixed to the bottom wall of the upper head and the recesses or openings 17 are formed 25 transversely in the free end portions of the posts. In that form of my invention illustrated in Figure 6, the order is reversed and the studs 16 are carried by the free end portions of the posts and are engageable 30 in the recesses 17 formed in the bottom of the upper head.

Referring to Figure 1, a member 18 is carried by the free end portion of each post and the openings 17 are formed therein. 35 The openings 17 accommodate a variance in the number of sheets 8 confined in the binder and the studs 16 are engaged in the openings 17 best suited for the number of sheets. For adjustments between adjacent openings 40 17, the threaded ends 19 of the innermost pivoted links 20 of the posts are adjusted in the extension sections 21 thereof, which form part of the posts and are secured to the lower binder head.

45 The outer ends of the members 18 preferably have angular finger pieces 22 riveted or otherwise secured thereon, as at 23, to facilitate the disengagement of the posts from the studs 16. As best illustrated in Figure 1, the ends of the openings 17 are 50 slightly flared or rounded and the ends of the studs 16 are rounded to facilitate the engaging or springing of the posts thereover while a slight tension is impressed on the posts. In operation, the upper head is pressed downwardly against the sheets 8 and the free end portions of the posts swung into the channel 15, the openings 17 55 registering with the studs 16 being sprung thereover. If the proper tension is not afforded by the engagement of the studs in the adjacent openings, the post portions 19 are threaded in or out of the extension sections 21 the desired distance, as will be 60 65 readily apparent.

The modified construction of my invention illustrated in Figure 2 eliminates all but one of the openings 17 in each member 18, and said member has a threaded stud 24 extended rearwardly therefrom which is 70 engaged in a turnbuckle 25 in the other end of which a stud 26 is threaded, the stud 26 being carried by the innermost pivoted link 27 of the adjacent post. In this form of my invention if the openings 17 fail to properly 75 register with the studs 16 after the upper binder head has been pressed against the leaves 8, the turnbuckles 25 are engaged at their knurled portions 28 and rotated to shorten or lengthen the posts, as the case 80 may be.

In Figures 3 and 4, a form of my invention somewhat similar to Figure 1 is illustrated wherein the member 18 is in the form of a sleeve and has a central bore 29 in which 85 a plunger 30 is slidable, the plunger having apertures 31 adapted to register with the apertures 17 of the member 18. The plunger 30 has a limited sliding movement in the bore 29 which is defined by a limit plug 32 carried thereby and working in a slot 33 formed in the side of the member. When the stud 32 engages the outer end of the slot 33, the apertures 17 and 31 are slightly disaligned and when the stud engages the other end of the slot the apertures are aligned. An expansion spring 34 is confined between the inner end of the bore 29 and the inner end of the plunger 30 to yieldably urge the plunger 30 to its position disaligning the 90 apertures.

The finger engaging piece 22 is secured to the end of the plunger 30 instead of to the member 18, and the openings 31 of the plunger are so flared at their ends that in 105 engaging one of the openings over the stud 16 the plunger 31 is moved inwardly against the spring 34 as will be apparent. With this construction the tension maintained on the stud 16 by the spring 34 normally tends to disalign the openings 17 and 31 and prevents dislodgement of the posts from the studs 16.

In Figure 5 another modification of my 110 invention is illustrated in which tension is applied to the pins or studs 16 in a slightly different manner and a slight variance in the number of sheets 8 in the binder is accommodated by the spring for applying the 115 tension to the pins. In this form of my invention, each member 18 has a rearwardly extending stud 35 which is slidable in the bore of a sleeve 36 carried by the outermost link 37 of the adjacent post, the stud 35 having an apertured lug 38 in which one end of a contractile spring 39 is secured, the other end of the spring 39 being fixed to the sleeve 36 at the inner end of its bore by a pin 40. As will be apparent, the springs 39 normally 120 125 tend to draw the studs 35 into the sleeves 36, 130

and, in securing the binder in closed position, the members 18 are extended against the tension of the springs 39 and the openings 17 thereof in alignment with the studs are engaged

5 gaged thereover, the tension of the springs 39 maintaining a pressure on the leaves 8 and preventing accidental disengagement of the members 18 from the studs.

In the forms of my invention previously 10 described, the studs 16 are carried by the upper binder head and in Figure 6 the order is reversed and the studs are formed on the finger engaging members 22 and are in the form of curved locking lugs or projections.

15 The finger engaging members 22 are carried by the outer ends of threaded studs 41 which are adjustable in tubes or sockets 42 carried by the free ends of the posts, sleeves 43 telescoping over the sockets 42 to conceal 20 that portion of the studs 41 extended therebeyond. The sleeves 43 are secured, as at 44, to shoulders 45 formed on the outer ends of the studs 41 and to which the finger engaging pieces 22 are riveted. The locking 25 studs or lugs 16 are curved in the manner illustrated in Figure 6 so that their outer ends, upon registering with the innermost edges of the adjacent openings 17 in the bottom of the binder head, will be engaged 30 therein upon application of pressure, the finger engaging piece curved portion engaging behind the edges of the openings.

From the foregoing description taken in connection with the accompanying drawings, 35 it will be readily obvious to those skilled in the art to which an invention of this character appertains that I have provided a very simple type of loose-leaf binder wherein variations in the number of sheets secured 40 therein may be readily accommodated and at the same time the construction of the binder is reduced to its simplest form to permit its manufacture at a relatively low cost.

45 What I claim is:

1. In a loose-leaf binder, an upper binder head member, a binder post member adapted to be adjustably connected with the head member and having one end portion normally free and extensible in said head member, 50 cooperating means between the post member and head member to adjustably and releasably connect the post member with the head member, said means including a stud carried by one member and engageable with a part carried by the other member, and means independent of said stud and part to accommodate relatively small adjustments between the members.

60 2. A loose-leaf binder, comprising a pair of binder heads, a post adapted to adjustably connect the heads, one end of the post being secured to one head and its other end portion being free and extensible in the second head, a plurality of attaching means carried by the post free end portion and spaced

longitudinally therealong, and means carried by the second head and engageable with the post carried means to connect the same with the head.

3. A loose-leaf binder, comprising a pair 70 of binder heads, a post adapted to adjustably connect the heads, one end of the post being secured to one head and its other end portion being free and extensible in the second head, and a stud carried by the upper binder head and selectively engageable in a plurality of apertures in the free end portion of the post to connect the same therewith against retraction.

4. A loose-leaf binder, comprising a pair 80 of binder heads, a post adapted to adjustably connect the heads, one end of the post being secured to one head and its other end portion being free and extensible in the second head, a stud carried by the upper binder head and engageable in any one of a plurality of apertures in the free end portion of the post to connect the same therewith against retraction, and means for shortening and lengthening the distance between 90 the free end portion of the binder post and the lower binder head to accommodate for adjustments between adjacent apertures.

5. A loose-leaf binder, comprising a pair 95 of binder heads, a post member adapted to adjustably connect the heads, one end of the post being secured to one head, an attaching member carried by the other end portion of the post and adapted to be connected with the second head, said member being extensible with respect to the post, and a stud carried by the upper binder head and engageable in an aperture in said member.

6. A loose-leaf binder, comprising a pair 100 of binder heads, a post member adapted to adjustably connect the heads, one end of the post being secured to one head, an attaching member carried by the other end portion of the post and adapted to be extensively secured in the second head, said member being 105 extensible with respect to the post, and a stud carried by the upper binder head and engageable in one of a plurality of apertures in said member.

7. A loose-leaf binder, comprising a pair 110 of binder heads, a post member adapted to adjustably connect the heads, one end of the post being secured to one head, an attaching member carried by the other end portion of the post and adapted to be extensively secured in the second head, said member being extensible with respect to the post, a stud carried by the upper binder head and engageable in one of a plurality of apertures 115 in said member, and spring means normally tending to draw said member to its retracted position.

8. A loose-leaf binder, comprising a pair of binder heads, a post adapted to adjustably connect the heads, one end of the post be-

ing secured to one head and its other end portion being free and extensible in the second head, a plurality of attaching means carried by the post free end portion and spaced longitudinally therealong, means carried by the second head and engageable with the post carried means to connect the post

with said head, and spring means adapted to exert a frictional contact between the post carried means and said second head carried means to prevent the accidental freeing of the post from the second head. ¹⁰

In testimony whereof I affix my signature.

HENRY C. MILLER.
